UNITED STATES PATENT OFFICE.

MARTIN E. BENGTSON, OF SPRINGFIELD, MASSACHUSETTS.

GAS-TURBINE.

1,255,852.

Specification of Letters Patent. Patented Feb. 12, 1918.

Application filed September 8, 1916. Serial No. 119,070.

To all whom it may concern:

Be it known that I, MARTIN E. BENGTSON, a subject of the King of Sweden, residing at Springfield, in the county of Hampden and State of Massachusetts, have invented certain new and useful Improvements in Gas-Turbines; and I do hereby declare the following to be a full, clear, and exact description of the invention, such as will enable others skilled in the art to which it appertains to make and use the same.

This invention relates to new and useful improvements in gas turbines and the principal object of the invention is to provide a turbine in which the explosive charge is compressed by means of a rotary compressor.

Another object of the invention is to provide a gas turbine having a plurality of explosion chambers open at opposite ends which are closed by the turbine wheel and compressor so as to insure the compressing of the charge within the device.

Still another object of the invention is to provide a water cooled motor of the rotary type having its explosion chamber completely water jacketed so as to avoid the possibility of the parts swelling and sticking.

With these and other objects in view the invention consists in the novel combination and arrangement of parts which will be fully set forth in the following specification and accompanying drawings, in which:

Fig. 1 is a side view in elevation of a turbine constructed in accordance with this invention.

Fig. 2 is a longitudinal sectional view through Fig. 1.

Fig. 3 is a transverse sectional view on line 3-3 of Fig. 1.

Fig. 4 is a transverse sectional view on line 4-4 of Fig. 2, and

Fig. 5 is a transverse sectional view on line 5-5 of Fig. 2.

Fig. 6 is a sectional view through the power rotor taken on the line 6-6 of Fig. 5 showing the V-shaped vanes in detail.

Referring to the drawing the numeral 1 designates the base of the device upon which the same is supported. The turbine comprises three separate shell members 2, 3 and 4 which are respectively known as the ex-

haust, explosion and intake chambers. Passing now to the detail description of each of the members we will first take up the description of the member designated by the numeral 2.

The member 2 comprises a wall 5 formed with a central outwardly extending hollow boss 6 which is preferably externally screw threaded at its outer end to support the cap 7. A central bore 8 extends through the body 5 and communicates with the opening in the boss 6 and at the point where the opening 8 and the central opening of said boss joins is formed a curved bearing 9 the use of which will appear as the description proceeds. Formed at the outer edge of the body 5 is a curved wall 10 which curves inwardly as at 11 and is provided at its extreme inner edge with a flange 12, the use of which will be more fully hereinafter described. The wall 5 and the curved portions 10 and 11 thereof are formed with a chamber 13 forming the water jacket for the exhaust side of the motor. In order to provide a means to let the exhaust gases escape, a suitable exhaust port 14 is formed in the plate or body 5 as clearly shown in Fig. 2.

Passing now to the description of the central section designated by the numeral 3, the numerals 15 and 16 designate respectively the outlet and intake rings of the member. These rings are connected at their inner and outer edges by the walls 17 and 18 the outer faces of the rings are machined off so as to form smooth surfaces against which the rotors run. Formed within the annular chamber formed by the rings 15 and 16 and the walls 17 are suitable walls 18 forming tapered explosion chambers 19 the reduced ends of which are disposed toward the exhaust chamber. Suitable tapered walls 20 join the walls 18 at their reduced end and flare outwardly toward the exhaust chamber as clearly shown in Fig. 2. The end of the chamber 19 opposite the reduced end opens into the intake chamber in which the compression rotor to be more fully hereinafter described is operable. Extending radially inwardly from the outer walls 17 is a plurality of hollow bosses 21 the inner ends of which communicate with the chambers 19 and these bosses are internally screw thread-

ed to receive the spark plugs 22 by means of which the compressed gases within the explosion chambers 19 are fired. It will thus be seen that when a charge is compressed within the explosion chamber the spark plug thereof is fired so that the spark jumps between its electrodes and ignites the charge thereby exploding the same and driving the burnt gases out through the passage 20 into the exhaust chamber, first passing the same through the vanes of the rotor.

Passing now to the description of the intake end of the device the same consists of the wall or body 23 provided at its periphery with the circular wall 24 which is in turn formed with a flange 25 which coöperates with the attaching flanges 26 of the central member. It will be understood that two of these attaching flanges are provided on the central member and one of the same coöperates with the flange 12 while the opposite coöperates with the flange 25 hereinbefore described. Formed centrally of the body or wall 23 is an outwardly extending hollow boss 27 provided with screw threads at its outer end by means of which the cap 28 is attached thereto. An annular row of openings 29 is formed in the body or wall 23 and surrounds the boss 27 to provide inlet ports by means of which the air and gases are admitted to the intake chamber. A suitable bore 30 extends through the wall 23 and communicates with the opening in the boss 27 and at the point where the bore 30 of the boss and the bore 30 join is formed a seat 31 which corresponds with the seat or bearing 9 of the wall 2.

Seated on the seats 9 and 31 are the spherical bodies 32 provided with the axial bores 33 which pass therethrough and are adapted to receive opposite ends of the shaft 34 on which the rotors are mounted. Suitable compression coil springs 35 bear against the caps 7 and 28 and the inner ends of said springs bear against the spherical bodies 32 to hold the same firmly against their seat. It will thus be seen that a pair of self-oiling bearings are provided for the drive shaft 34 of the device.

Passing now to the description of the compressor rotor the numeral 36 designates the hub thereof which is formed integrally at the center of the disk 37 forming the body of the rotor. This disk or body is provided with the inlet ports or openings 38 which are arranged in annular series near its periphery, and intermediate the ports are formed the radiating ribs 39 which form the fan blades by means of which the rushing gas is compressed in the explosion chamber. Attached within the intake chamber and arranged adjacent the outer sides of the ribs 39 is a wall 40 provided with the outturned central portion 41 having formed centrally thereof the intake port 42.

It will thus be seen that when the compressing rotor is operated the same will have the effect of a centrifugal fan blower and the fluid drawn in through the opening 42 will be expelled through the openings 38 and into the explosion chambers.

After the explosion takes place in the explosion chamber the gases pass between the vanes of the power rotor which is designated generally by the numeral 43. This rotor comprises the hub 44 having an annular flange 45 formed at its periphery which flange is formed at spaced intervals with openings 46 in which the vanes 47 are formed. These vanes are V-shaped as illustrated in Fig. 2, and it will be seen that the exploding gases passing through the passage 20 will be directed against the walls of the vanes, thereby setting the device in motion.

It will be apparent from the foregoing that in use the device must first be started by any suitable prime mover and after it has obtained a predetermined speed the gas is admitted to the intake chamber and it will be drawn through the opening 42 and forced through the opening 38 from whence it will pass into the explosion chamber 19. Upon the firing of the gases it will be evident that the certain expansion thereof will exert a pressure against the vanes 47, thereby setting the motor in operation under its own power. It will then be evident that the prime mover may be disconnected and the motor allowed to run without further assistance.

While in the foregoing there has been shown and described the preferred embodiment of this invention, it is to be understood that such changes may be made in the combination and arrangement of parts as will fall within the spirit and scope of the appended claim.

What is claimed is:

In a device of the class described, a wall forming an intake chamber, said wall being provided with an annular series of openings near its center, a bearing mounted centrally of the wall, walls at the opposite end of the first mentioned wall forming a plurality of annularly disposed explosion chambers, a wall forming an exhaust chamber on the side opposite the intake chamber, a bearing centrally of the last mentioned wall, a shaft rotatable in the bearings, the last named wall having an exhaust port therein, a compression rotor mounted on the shaft within the intake chamber, a guard wall within the intake chamber mounted in close proximity to the compression rotor, means to draw in the explosive charge from the intake chamber and force the same into the explosion chambers, the said rotor having a plurality of intake openings formed between the ribs whereby the charge admitted to the explo-

sion chamber will be compressed, an operating rotor mounted on the opposite end of the shaft and running against the opposite side of the explosion chambers, said rotor being provided with an annular series of openings, and a plurality of vanes in the openings against which the exploded gases impinge, the said openings being arranged

in staggered relation to the openings in the compression rotor.

In testimony whereof I affix my signature in presence of two witnesses.

MARTIN E. BENGTSON.
